UNITED STATES PATENT OFFICE.

STANLEY KRASON, OF GARY, INDIANA.

BANK-BOX.

1,333,177.

Specification of Letters Patent.

Patented Mar. 9, 1920.

Application filed May 28, 1919. Serial No. 300,368.

To all whom it may concern:

Be it known that I, STANLEY KRASON, a citizen of Poland, having declared his intention to become a citizen of the United States of America, residing at Gary, in the county of Lake and State of Indiana, have invented certain new and useful Improvements in Bank-Boxes, of which the following is a specification.

10 The primary object of the invention is the provision of a safety box or case for a bank employee or a railway mail clerk whereby he may be protected in the event of a raid upon the bank or of the mail, the 15 structure possessing great strength as well as being fire and bullet-proof.

A further object of the invention is to provide a box adapted for various uses whereby any object suddenly descending 20 upon the floor thereof automatically releases the door for closing to its locked position retaining the entrapped contents against the efforts there without to obtain the same either by the use of fire-arms or fire.

25 With these general objects in view the invention consists of the novel combination and arrangement of parts hereinafter more fully described, in connection with the accompanying drawings and in which like reference characters designate corresponding parts throughout the several views.

In the drawings,

Figure 1 is an elevational view of the invention open,

35 Fig. 2 is a horizontal sectional view taken upon line II—II of Fig. 1,

Fig. 3 is a front elevation of the invention closed partially broken away,

40 Fig. 4 is a view similar to the lower portion of Fig. 1, with the door partially broken away showing the latch in place,

Fig. 5 is a vertical sectional view taken upon line V—V of Fig. 2,

45 Fig. 6 is an enlarged horizontal detail sectional view of the locking catch in position and

Fig. 7 is a perspective view of an end portion of the latch employed.

50 My invention broadly consists of a box 10 triangular in horizontal cross section with one side 11 thereof in the form of a hinged door having closing springs 12 adjacent its hinges 13, the bottom 14 and top 15 of the box being in the form of an equilateral triangle.

A resilient latch 16 is secured as at 17

upon the bottom of the box being bent upwardly with a spring 18 between the bottom 14 and the latch for normally retaining the arcuate end portion 19 of the latch elevated. 60 The latch portion 19 normally projects through a slot 20 in the door 11 and is provided with a shoulder 21 having an inclined inner face 22 so that upon opening the door 11, the shoulder 21 automatically engages 65 the door 11 at the upper edge of the slot 20 for retaining the door open until the latch 16 is released.

A false bottom or platform 23 triangular in shape rests upon coil springs 24 carried 70 by the box bottom 14 and upon the deposit of any considerable weight upon the platform 23, the platform is depressed, engaging the latch 16 and tripping the shoulder 21 out of engagement with the door 11. The 75 door being released in this manner, the springs 12 automatically swing the door to its closed position where a plurality of spring catches 25 automatically engage over lugs 26 upon the adjacent edge of the box 80 side and the door is locked in its closed position.

The upward movement of the platform 23 is limited by inwardly projecting stops 27 upon the sides of the box, the operation of 85 the release of the latch 16 however being evident whether a weight such as express packages or mail are thrown into the box or a person jumps into the box upon the platform 23, in either event, the door 11 quickly 90 springs closed retained by the latches 25 and the box being formed of bullet-proof as well as fire-proof sheet metal, the obtaining of its contents from outside persons is extremely difficult. When a person is located 95 in the box however, the latches 25 may be released by pulling inwardly upon the handles 28 carried by the catches 25.

The invention is simple and strong in construction but capable of protecting life and 100 property in the event of a raid by marauders. A plurality of ventilating perforations 29 are provided through the sides of the box adjacent the top thereof.

While the form of the invention herein 105 set forth is believed to be preferable, minor changes may be made without departing from the spirit of my invention.

Having thus described my invention what I claim and desire to secure by Letters Patent is:-

1. A device of the class described com-

prising a box triangular in cross section having one hinged side forming a door with a slot provided therethrough, adjacent the bottom of the box, a resilient latch secured to the bottom of the box having an arcuate portion projecting outwardly thereof through the said slot, a shoulder upon the curved portion of the latch having a beveled inner face adapted for the automatic seating reception of the portion of the door above the slot outwardly of said shoulder when the door is opened, an elevating spring beneath said latch upon the floor of the box, closing springs for the door when the latch is released and automatic means for releasing the latch when a weighted member is deposited in the box.

2. A device of the class described comprising a box triangular in cross section having one hinged side forming a door with a slot provided therethrough, adjacent the bottom of the box, a resilient latch secured

to the bottom of the box having an arcuate portion projecting outwardly thereof through the said slot, a shoulder upon the curved portion of the latch having a beveled inner face adapted for the automatic seating reception of the portion of the door above the slot outwardly of said shoulder when the door is opened, an elevating spring beneath said latch upon the floor of the box, closing springs for the door when the latch is released, a triangular platform within the box above the latch, elevating springs for the platform upon the bottom of the box, limiting lugs for the upward movement of the platform, spring-catch devices adapted to automatically retain the door in its closed position, the platform being adapted for depression upon receiving a load whereby the latch is released and the door automatically closed to its locked position.

In testimony whereof I affix my signature.
STANLEY KRASON.
